1**2,983,992****METHOD FOR FABRICATING TURBINE ASSEMBLY**

David J. Bloomberg, Newton, Mass., assignor to David J. Bloomberg, Inc., Newton, Mass., a corporation of Massachusetts

Filed Feb. 7, 1957, Ser. No. 638,789

7 Claims. (Cl. 29—156.8)

My invention relates to improvements in methods of turbine fabrication and to turbines fabricated according to said improved methods.

More particularly, my invention relates to improved methods of fabrication of turbine bucket or nozzle assemblies and improved methods of fastening bucket assemblies to turbine wheels.

Still more particularly, my invention relates to improved ways of preheating bucket assemblies for mounting on wheels, said preheating and mounting being accomplished without damage to the buckets or appreciable oxidation thereof, thereby permitting secure fastening of the buckets to wheels cast in contact therewith.

For reasons such as proper stress distribution, it is often desirable to make turbine buckets of material which is different from that which is employed in the turbine wheels. This fact necessarily implies that a wheel and its buckets often cannot initially be made in one piece, and that the buckets must somehow be joined to the wheel. Such joints must necessarily be very strong in order to be capable of standing the stresses which exist in turbines at high speeds. In the past, buckets have been fastened mechanically to the wheel, but such a method of fastening becomes increasingly inconvenient and difficult in view of two considerations. The first of these considerations is the demand for rapid mass production of turbines, especially gas turbines and special turbines for missiles. The second consideration is the fact that aviation turbines demand light weight, and the additional fact that one way to lighten the turbine is to make the wheel disc as thin as possible, and the buckets as narrow as possible. Not only does narrowing the buckets tend to increase the difficulty of fastening the buckets to the wheel, but also such narrowing of the buckets tends to aggravate any tendency of the buckets to vibrate.

One way to handle the problem of fastening the buckets to the turbine wheel is to place the buckets in position around the periphery of a circle and then pour molten metal into a properly shaped mold, such that the molten metal forms a wheel and fuses the innermost ends of the buckets, thereby fastening the buckets to the wheel as formed by the molten metal. In order to permit the molten metal to fuse the ends of the buckets upon contacting them, the buckets themselves must be preheated to a temperature not too far below that of the molten metal. In other words, in order to get a satisfactory fused joint between the buckets and the wheel, the buckets must be prevented from conducting away too much of the heat from the molten metal. Such excessive heat conduction is prevented by preheating the buckets to a temperature approaching that of the molten metal. However, preheating the buckets for any appreciable length of time in the atmosphere tends to produce oxidation of the buckets, and any serious oxidation of the ends of the buckets prevents the formation of a satisfactory fused joint between the buckets and the molten metal. It has been attempted to prevent this oxidation by pre-

2

heating the buckets by means of induced high-frequency electric currents and by making the heating period so intense and brief that no serious oxidation can take place.

The results of this method have not been entirely satisfactory. One defect of this method is the fact that a short, intense period of preheating the buckets themselves may alter the crystalline structure of the bucket shanks in such a way as to impair the strength of the metal in a place where strength is of the utmost importance.

Accordingly, it is an object of my invention to provide a method whereby turbine buckets may be preheated for attachment to a molten wheel without said turbine buckets becoming seriously oxidized or impaired in strength.

It is another object of my invention to provide a way in which turbine buckets or nozzle diaphragms may be conveniently pre-cast and maintained in proper position for further fabrication operations.

20 It is still another object of my invention to provide turbine wheel assemblies which are strong, light, and resistant to vibration.

It is a still further object of my invention to provide a turbine fabrication method which is simple, convenient, 25 and capable of a high degree of automatization.

Briefly, I am able to fulfill these and other objects of my invention by pre-casting an assembly of buckets arranged around the periphery of a circle, each bucket being integral with the adjacent portion of a pair of rings 30 cast at the same time as the buckets, one ring being positioned on either side of the shanks of the buckets. Preheating of the buckets preparatory to the pouring of a cast wheel is accomplished by inducing a high-frequency electric current in the rings, whereby the buckets 35 are pre-heated indirectly by thermal conduction from the rings, the preheating process being carried out in a vacuum or an inert atmosphere. The rings, which are expendable, may later be machined away, leaving the buckets securely joined to the wheel cast in contact with 40 them.

For a full understanding of my invention, reference is made to the following complete specification, taken in conjunction with the appended claims and the accompanying drawings, wherein:

45 Fig. 1 is a fragmentary view of a pre-cast assembly of turbine buckets and expendable preheating rings;

Fig. 2 is a modified sectional view taken through a bucket and its preheating rings, and showing by dash lines the position, relative to the bucket, where the turbine wheel may be cast;

50 Fig. 3 is a modified sectional view of a mold in which the wheel may be cast, showing associated apparatus and showing the position of the buckets and rings during casting of the wheel; and

55 Fig. 4 is a modified sectional view through a portion of a turbine wheel assembly, showing damping rings which may be installed for minimization of bucket vibration.

In order to facilitate a clear explanation of my invention, it may be helpful first to offer a brief explanation of the terms to be used in the specification. For the purpose of the explanation, reference will be made to Fig. 1 of the drawings.

A finished turbine wheel consists of a more-or-less disc-shaped object with a large number of "buckets" attached around its periphery. Properly speaking, the "wheel" is the disc-shaped object alone, without the buckets. The word "wheel" will be used in that sense in the following paragraphs. Sometimes one may find the word "wheel" used to mean the assembly of disc and buckets, but this specification will use the words "wheel assembly" if both the disc and the buckets are meant to be included. Each

bucket consists of a blade 11, a base 12 of blade 11, and a shank 14, as shown in Fig. 2 and Fig. 4, as well as in Fig. 1. The modified sectional views of Fig. 2 and Fig. 4 are such as would be obtained if a plane were passed through a bucket, the longitudinal axis of the bucket being in the plane. The orientation of the plane is also such that, when the bucket is installed on a turbine wheel, the plane would pass through the radius of the wheel and would be normal to the wheel. The two shaded portions, 16 and 17, of Fig. 2 represent cross sections of the expendable heating rings, and have been shaded in order to distinguish the rings from the buckets and from the space to be occupied by the turbine wheel. The cross sections of the bucket and of the rings are, of course, formed by the same plane.

As for the method by which the pre-cast assembly of Fig. 1 may be produced, it is sufficient to say that the assembly may be produced by means of familiar techniques, such as by pouring the assembly in a special shell mold. In preparing the shell mold, care should be taken that the bucket spaces are regularly arranged, with their inner and outer extremities on respective concentric circles. Likewise, care should be taken that the portions of the mold which are to shape faces 18 and 19 of the respective rings are accurately formed, for the turbine wheel is to be poured in contact with those faces. The ring-defining cavities in the mold may serve as "headers," through which molten metal may be passed to form the buckets in the bucket-defining cavities of the mold. The amounts by which the rings 16 and 17 overlap the buckets and the turbine wheel should be sufficient to permit good thermal contact. In particular, it is important that rings 16 and 17 overlap shanks 14 of the buckets sufficiently to permit good heat transfer from the rings to the buckets during the preheating operation. The pre-cast assembly of buckets and two rings forms an entity which is easy to make and easy to handle after it has been made.

After the pre-cast assembly of buckets and rings is removed from the mold in which it was cast, the assembly is placed in a second mold and may then appear as in Fig. 3, which is a modified sectional view of the mold in which the turbine wheel is to be cast. In Fig. 3, the portion of the pre-cast assembly which is diametrically opposed to that portion shown in Fig. 2 appears at the left-hand side of Fig. 3. The section of the ring shown at 26 is a portion of the same ring shown in section at 16, while the section of the ring shown at 27 is a portion of the same ring shown in section at 17. The mold has a lower portion 31, an upper portion 32, and a case 33. Once again, the mold comprising portions 31 and 32 may be a shell mold manufactured by conventional techniques. The cavity for receiving molten metal to form the wheel and shaft is designated generally by the numeral 35. Guides, not shown in Fig. 3, would be provided in order to support the mold in case 33.

A pair of induction-heating coils 41 and 42 are shown in Fig. 3, wherein induction-heating coil 42 may be retained in position by a series of supports such as those shown at 43. Induction-heating coils 41 and 42 should be positioned as near to the expendable preheating rings as the design of the mold will permit, thereby providing for maximum magnetic flux linkage between the coils and the rings. Induction-heating coils 41 and 42 may be cooled by water flowing through the hollow interiors of the respective coils. For reasons of safety, the induction-heating coils should preferably be outside the confines of the mold because, if molten metal were to come into contact with the coils, some of the cooling water within the coils might be vaporized so rapidly as to cause an explosion. By employing a shell mold, I am able to achieve a thin mold wall, so that the induction-heating coils may be brought into close proximity with the expendable preheating rings without being placed within the enclosure of the mold. I prefer to employ induction-heating coils which are circular, and which are mounted

in planes parallel to those defined by the expendable preheating rings. Thus, when high frequency voltages are applied respectively to coils 41 and 42 through electrical leads shown schematically at 45 and 46, each coil induces a heating current in the ring adjacent to it. Each ring behaves in a manner comparable to the short-circuited secondary winding of a transformer of which the corresponding induction-heating coil is the primary winding.

While induction-heating coils 41 and 42 might each comprise a number of turns, I prefer to employ coils each of which comprises a single turn. It will be understood that each induction-heating coil should be served by a pair of electrical leads, which should preferably be connected to the coil at points located close together, thus insuring uniform heating of the preheating rings. The high-frequency voltage may be obtained from any suitable commercially-available high-frequency generator.

When the pre-cast assembly is placed in the mold, and a high-frequency potential (of the order of 500 kilocycles per second, for instance) is applied to the induction-heating coils, the preheating of the pre-cast assembly begins. While the induction-heating coils are hollow and have cooling water flowing in them, the preheating rings become very hot and supply heat by thermal conduction to the shanks of the turbine buckets adjacent to them. Inasmuch as the rings are integral with the buckets, and inasmuch as there are two rings supplying heat to the buckets, the buckets can be suitably preheated by thermal conduction without having substantial induced currents flowing in them. Although the temperatures of the rings may reach levels such that the strength of the rings is impaired, the temperatures of the buckets do not reach levels sufficiently high to damage the buckets. One way to prevent the temperatures of the buckets from reaching high levels is to form the buckets so that adjacent buckets are not in contact and, therefore, do not form a continuous path for an induced circulating current. Buckets may, if desired, be pre-cast with removable ceramic investments between them to prevent contact. The fact that the rings may suffer metallurgical damage does not matter, because the rings are to be machined away after the turbine wheel has been cast and after the rings have served their purpose. It will be noted that the rings overlap the shank ends of the buckets and embrace part of the space into which the wheel is cast.

Now, inasmuch as the buckets are preheated by thermal conduction rather than by induced currents flowing in the buckets themselves to any great extent, it is well to allow more time for the preheating process than with prior-art types of preheating processes. Therefore, according to my invention, oxidation of the buckets is prevented by carrying out most of the preheating process under vacuum conditions. In Fig. 3, I have shown a vacuum cap 48, which permits the mold to be evacuated and to remain sealed during the preheating period. The atmosphere in the mold may be drawn off through vacuum lines shown schematically at 49 and 50. By leaving a small amount of clearance between the mold and the pre-cast assembly, I am able to permit the air in the mold to get past the pre-cast assembly to the vacuum lines without also having the molten metal get into the vacuum lines. If there is a clearance of approximately 10 mils between the mold and the top of the pre-cast assembly, the air will be able to pass through the clearance without being followed by the molten metal to be poured into the mold cavity 35. If mold 31 is a shell mold with relatively thin walls, it is desirable to equip the outer surface of the mold with ribs, thereby making the mold sufficiently rigid to withstand without substantial deformation the pressure of the atmosphere after the air has been evacuated from the interior of the mold. It is also desirable to provide a gasket of some sort between the mating edges of the lower portion 31 and the upper portion 32 of the mold.

Although vacuum cap 48 is removed from the mold during the pouring of molten metal into the mold, the period of time during which the buckets are thereby exposed to the air is comparatively short. If the vacuum conditions are maintained in the mold during the pre-heating process, the brief period when the vacuum is spoiled just prior to the pouring of the molten metal into the mold will not be sufficient to permit serious oxidation of the buckets.

The same source of vacuum as was used in evacuating the air from the mold may also be used for the purpose of drawing the cooling water out of induction-heating coils 41 and 42 immediately after the end of the pre-heating period and before the introduction of molten metal into the mold. Such withdrawal of the cooling water would be particularly important if the induction-heating coils were placed within the cavity of the mold. As aforementioned, I prefer to place the induction-heating coils just outside the mold rather than within it, thereby avoiding any risk of sudden generation of steam within the coils if residual cooling water should remain in the coils. By choosing to evacuate the air from the mold through vacuum lines which are connected to the mold near its outer periphery, I not only achieve convenient and safe evacuation of the mold but also am able to draw the molten metal into all the portions of the mold which I desire to fill with metal. For this purpose, evacuation of air through the vacuum lines may be continued during the pouring of molten metal, even though at that time vacuum cap 48 is not in place on the mold.

The process according to my invention is suited to a high degree of automatization, in that a series of molds, each carrying a pre-cast bucket-and-ring assembly, may be carried on a moving belt or conveyor, passing under a kettle of molten metal from which their respective wheel cavities are successively filled. Of course, each of the pre-cast assemblies would be preheated to the proper temperature by the time it reached the kettle, and the preheating would be done under no-oxygen conditions. Such an arrangement could be achieved by using flexible leads to the induction heater or high-frequency generator, flexible cooling-water lines, and flexible vacuum lines. It will be appreciated that, while this discussion has assumed that bucket oxidation is to be prevented by pre-heating of the buckets under vacuum, oxidation of the buckets might also be prevented by preheating the buckets in an inert gas such as argon.

Whether one considers the process of fabrication, the apparatus employed in the fabrication, or the nature of the finished turbine wheel, a number of modifications may be made without departing from the scope of my invention. For instance, the length of time during which preheat should be applied to the buckets will depend upon the desired temperature differential between the preheated buckets and the molten metal which is to form the turbine wheel. The desired temperature differential may in turn depend upon the nature of the metals which are employed for the buckets and for the wheel, respectively. If different steel alloys are employed for the buckets and for the wheel, respectively, the temperature of the molten wheel metal may be about 2400 degrees F., and it may be desired to preheat the buckets to a temperature of the order of 1700 degrees F.

As for the apparatus employed in the fabrication, it is clear that automatic controls may be employed for purposes such as starting and stopping the conveyor carrying the molds, and for applying and cutting off the preheating current, cooling water, and the vacuum or inert gas. Similarly, automatic apparatus may be employed for removing the vacuum cap from the mold and for tapping the kettle of molten metal. If desired, the kettle, as well as the turbine buckets, may be heated by means of high-frequency induction apparatus.

If automatized apparatus is employed for controlling

75

the preheating and pouring steps in each one of a series of molds, the controls should be capable of going through the following sequence of steps for each mold into which a pre-cast assembly of buckets and rings has been placed:

- 5 (1) Apply vacuum to the mold.
- (2) Apply cooling water and a high-frequency potential to the induction-heating coils.

- (3) Cut off high-frequency potential and cooling water when preheating has been accomplished and mold has

10 been placed under kettle.

- (4) Remove vacuum cap from mold and fill mold with molten metal from kettle.

If a mold conveyor is employed, provision should be made for intermittent motion of the conveyor, whereby 15 each mold may dwell beneath the kettle long enough for the pouring to be completed. Of course, it might for some purposes be preferable to keep the molds stationary and to move the kettle into the various pouring positions.

20 With regard to the various modifications which may be made in the bucket assembly and in the finished turbine wheel assembly, it may be pointed out that there may conceivably be occasions when one may not wish to cast the buckets and the preheating rings integrally.

25 If such occasions should arise, the buckets and the preheating rings may be separately prepared and may be clamped or welded together for placement in the mold for preheating and for pouring of the turbine wheel.

The turbine wheel assembly may be modified, within 30 the scope of my invention, by providing means as illustrated in Fig. 4 for the damping out of any residual tendency toward bucket vibration. The configuration of Fig. 4 resists bucket vibration by means of a pair of ductile damping rings 52 and 53 which are respectively installed in notches in the inner faces of the two sides 12 and 13 of the turbine bucket bases. Such damping rings (two rings per wheel assembly) contact all the turbine buckets and, by friction against the individual buckets, substantially damp out vibration of the

35 buckets. In order to take maximum advantage of damping rings 52 and 53, the buckets may be designed in such a way that the shanks are comparatively long and flexible and the damping rings are installed at the outer extremities of the shanks, thereby maximizing the radius 40 of the damping rings. Inasmuch as the damping rings are held in notches on the inner sides of the turbine blade bases, the rings are forced more and more firmly into place as the speed of the turbine increases. Consequently, the frictional damping action increases as the

45 turbine speed and tendency toward vibration increases. Being formed of ductile metal, the damping rings are capable of stretching to the degree which is necessary to maintain close contact with the turbine-bucket blade bases.

50 55 As has been previously stated, preheating rings which are integrally pre-cast with the turbine buckets may be machined away after they have served their multiple purpose. Fig. 4 represents the appearance of a portion of a turbine wheel assembly after the preheating rings 60 have been removed. The turbine wheel 57 is fused to the bucket shanks as shown at 58, and the preheating rings no longer appear in their respective positions on either side of fused joint 58. It has been shown that pre-cast preheating rings serve the following purposes:

- 65 (1) To serve as "headers" through which molten metal can flow during the casting of the buckets.
- (2) To hold the buckets in proper relative positions after the pre-casting operation and prior to the casting of the turbine wheel.

- (3) To serve as short circuits for carrying heating currents, and to transfer the heat to the shanks of the buckets for preheating the buckets without metallurgically damaging them.

70 Although the foregoing disclosure has been in terms

of the fabrication of turbine wheel assemblies, it is clear that the same principles of pre-casting rings, preheating components by thermal conduction from those rings, and preheating in an oxygen-free atmosphere might also be employed in the fabrication of nozzle-diaphragm assemblies. Accordingly, I intend to cover by means of the appended claims all those modifications of turbines and fabrication processes which are properly within the scope of my invention.

What I claim as novel and desire to secure by Letters Patent of the United States is:

1. A process for the fabrication of a machine assembly comprising the steps of prefabricating a subassembly including a plurality of non-contiguous components and at least one electrically conductive expendable annular member in thermally conductive relationship with each of said components, preheating said components by inducing an electrical current in said annular member and allowing heat to flow from said annular member into said components, casting a central unifying structure and simultaneously effecting fusion of said heated components to said central unifying structure, and thereafter removing an expendable portion of said annular member.

2. A process according to claim 1, wherein said pre-heating step is carried out in an environment having a concentration of oxygen smaller than that of atmospheric air.

3. A process according to claim 1, wherein said pre-heating step is carried out in an environment characterized by a pressure smaller than that of the atmosphere at standard conditions.

4. A process according to claim 1, wherein said pre-heating step is carried out in an inert gas.

5. A process for the fabrication of a turbine wheel assembly comprising the steps of prefabricating a subassembly including a plurality of non-contiguous buckets and at least one electrically conductive expendable an-

25 nular member in thermally conductive relationship with each of said buckets, preheating said buckets by inducing an electrical current in said annular member and allowing heat to flow from said annular member into said buckets, casting a central turbine wheel and simultaneously effecting fusion of said heated buckets to said central turbine wheel, and thereafter removing an expendable portion of said annular member.

6. A process according to claim 5, wherein said buckets are preheated substantially out of contact with oxygen.

7. A process for the fabrication of a turbine wheel assembly comprising the steps of prefabricating a subassembly including a plurality of non-contiguous alloy-steel buckets and a pair of electrically conductive expendable alloy-steel rings in thermally conductive relationship with each of said buckets, preheating said buckets by inducing electrical currents in said rings and allowing heat to flow from said rings into said buckets, casting a central turbine wheel and simultaneously effecting fusion of said heated buckets to said central turbine wheel, and thereafter removing an expendable portion of each of said rings.
